UNITED STATES PATENT OFFICE.

FRANK C. SMITH, OF MINNEAPOLIS, MINNESOTA.

EXPANSION-TANK.

1,149,865.

Specification of Letters Patent.

Patented Aug. 10, 1915.

Application filed November 24, 1914. Serial No. 873,760.

To all whom it may concern:

Be it known that I, FRANK C. SMITH, citizen of the United States, resident of Minneapolis, county of Hennepin, State of Minnesota, have invented certain new and useful Improvements in Expansion-Tanks, of which the following is a specification.

My invention relates to expansion tanks designed particularly for use in connection 10 with hot water heating systems.

It often happens in mounting an expansion tank that if a certain unchangeable opening is provided in the tank for the water supply pipe and another unchangeable opening 15 for the waste or overflow pipe, the plumber or mechanic making the connection is obliged to spend considerable time in adjusting the supply and overflow pipes to meet these openings, it often being necessary 20 to bend or twist the pipes past one another, necessitating frequently the use of elbows, T's, and the like. Furthermore, the usual connection in the bottom of the tank for these pipes requires the use of unions in 25 making the necessary attachments and adds considerably to the expense of installing the tank.

The object, therefore, of my invention is to provide an expansion tank to which the 30 supply and overflow pipes can be connected, without the use of unions and without the necessity of connecting each pipe to an opening previously designed or equipped for such connection.

35 The invention consists generally in various constructions and combinations, all as hereinafter described and particularly pointed out in the claims.

In the accompanying drawings forming 40 part of this specification, Figure 1 is a front elevation of an expansion tank embodying my invention, Fig. 2 is a vertical sectional view, showing the interchangeable form of connections between the supply and over- 45 flow pipes and the bottom of the tank.

In the drawing, 2 represents a sheet metal 50 expansion tank of ordinary construction, having a bottom 3. This bottom is provided with holes 4 and 5. 6 and 7 are supply and 55 overflow pipes, each pipe being adapted to fit loosely into either one of the holes 4 and 5. Oftentimes when the tank is set up in a corner of a closet, of some confined space in the building, considerable time and labor 60 are required to bring the supply and over-

flow pipes around to the point beneath the tank where they can be conveniently connected thereto if a certain connection is provided in the bottom of the tank for each pipe. When the tank has been set up and 60 the pipes brought up through the floor, the plumber or heating man may find that the supply pipe is on the right hand, while the connection for it to the tank is on the left, necessitating the bending of the pipes past 65 one another to enable the proper connections to be made. Then, too, the bottoms of these tanks are usually provided with plates fastened over the openings and threaded to receive the threaded ends of the pipes, necessitating, of course, the use of unions in the 70 pipes immediately below the tank. To obviate these objections, I provide openings in the bottom of the tank adapted to loosely receive either pipe, according to its location 75 with respect to the holes in the tank, and when these pipes have been inserted into the holes 4 and 5, I clamp them against the bottom of the tank by means of lock nuts 8 having gaskets 9 interposed between them 80 and the bottom of the tank. The threaded ends of these pipes extend upwardly into the tank and on the end of the supply pipe 4 I provide a similar lock nut 8', also having 85 a gasket interposed between it and the tank bottom and thereby the supply pipe will be securely mounted in the tank bottom without the use of unions or similar connections. The overflow pipe 7 preferably extends a 90 greater distance into the tank than the supply pipe and a sleeve 10 is mounted thereon, being interiorly threaded to engage the threads of the pipe, the threaded opening in the lower end of the sleeve being preferably of greater diameter than the continuation of the opening in the upper part of the sleeve, so that the inner wall of the waste 95 pipe and the wall of the sleeve at the upper end thereof will be substantially flush with one another, to avoid obstructing the pipe, 100 as indicated in Fig. 2. A gasket 11 is interposed between this sleeve and the bottom of the tank and when the sleeve is tightened, a firm connection will be made between the waste pipe and the tank bottom. The usual 105 sheet metal overflow 12 is mounted on the sleeve 10 and projects up into the tank the desired distance to carry away the water when it rises above a predetermined point in the tank. This overflow is shown on the 110

left hand side of the tank, but if for any reason it should be preferable to connect the waste pipe to the opening in the right hand side of the tank, the overflow can be substituted for the supply pipe connection and thereby the necessity of bending the pipes or using T's or elbows to carry them past one another is entirely avoided, and a great deal of time and labor is saved in the installation of the system.

10 I claim as my invention:

1. An expansion tank having two openings in the bottom thereof, and supply and waste pipes having threaded ends projecting loosely through said openings into the tank and each having a locking member for said threaded ends on the inside and outside of the tank and seated against opposite sides of the bottom thereof, an overflow pipe mounted on the inner locking member of said waste pipe, said supply and waste pipes being interchangeable in said openings for

convenience in making the connections to said tank.

2. An expansion tank having two holes in 25 the bottom, a water supply pipe and a waste pipe having threaded ends fitting loosely within said holes and projecting into said tank, a lock nut and gasket mounted on each pipe below said bottom, a lock nut and 30 gasket on said supply pipe above said bottom, and an overflow pipe having a threaded base to engage the projecting end of said waste pipe and inner side of the said bottom, the tightening of said lock nuts and 35 base clamping said pipes on the bottom of said tank.

In witness whereof, I have hereunto set my hand this 21st day of November 1914.

FRANK C. SMITH.
